HUBERT KREUELS, OF KREFELD, GERMANY.

REBOUNDING BOW.

Application filed August 20, 1927. Serial No. 214,368.

Rebounding bows for the pickers of looms with multiple shuttle-change have become known, in which leather-strips placed the one on the other are used as a double bow in **S**-shape. The rebounding bow according to the invention, differs from the rebounding bows of known type in that the leather-strips, or one leather-strip and one strip of spring-steel, are of equal length, their bores being displaced the one with regard to the other, said strips being then riveted together so that each individual strip is freely elastic in the bent-portions. The elasticity of the rebounding bow is thus increased to a multiple and the duration of the same is lengthened. The striking points are further strengthened by means of plates of vulcanized fibre or aluminum, this material having proved to be best suited for the purpose.

The improved rebounding bow, according to the invention is shown, by way of example, in the accompanying drawings in which:—

Figs. 1 and 2 are two similar top plan views, Fig. 1 showing a spring-steel-strip and Fig. 2 a leather-strip.

Fig. 3 shows in side elevation the rebounding bow ready for use.

Fig. 4 is a top plan view of Fig. 3.

Each strip, the spring-steel-strip *a* and the leather-strip *b*, has three holes *c* through which the picker-spindle passes, the middle hole *c* in the one strip being displaced with regard to that of the other strip. As shown in Figs. 1 and 2 the middle hole *c* in the strip *a* is slightly displaced to the right from the middle, the corresponding hole *c* in strip *b* being displaced from the middle to the left at the same distance as the middle hole *c* in the strip *a* is displaced to the right. When the

strips *a*, *b* are fixed the one on the other by rivets so that the corresponding holes *c* register the one with the other, a free space will be produced, as shown in Fig. 3, between the two strips at the bent portions, whereby the individual elasticity of the two strips is preserved in such a manner that each strip can bend in the bends until it comes into contact with the other strip. As in service the rebounding bow is completely compressed, strengthening plates *e* of vulcanized fibre are fixed on the striking points by means of rivets.

I claim:—

1. A rebounding bow for pickers of looms, composed of several strips of equal length riveted together and bent in **S**-shape, in which the two strips, having each bores for the picker-shaft the middle bore in the one strip being displaced with regard to that of the other strip, are riveted the one on the other in such a manner that in each bend a free space remains between said two strips, and plates of suitable material as vulcanized fibre riveted on the striking points.

2. A rebounding bow for pickers of looms, comprising in combination a strip of spring-steel, and a strip of leather of equal length and having each holes of which the middle one in the spring-steel-strip is slightly displaced to the right of the middle the middle hole in the leather-strip being slightly displaced to the left of the middle said two strips being riveted the one on the other or bent in **S**-shape so that in each bend a free space is formed between said two strips, and plates of aluminum fixed by rivets on the striking points of said bow.

In testimony whereof I affix my signature.
HUBERT KREUELS.
